UNITED STATES PATENT OFFICE.

G. H. PEABODY, OF COLUMBUS, GEORGIA.

IMPROVEMENT IN COTTON-PICKERS' WALLETS.

Specification forming part of Letters Patent No. 26,288, dated November 29, 1859.

To all whom it may concern:

Be it known that I, G. H. PEABODY, of Columbus, in the county of Muscogee and State of Georgia, have invented a new and Improved Cotton-Picker's Wallet; and I do hereby declare that the following is a full, clear, and exact description thereof, reference being had to the accompanying drawings, forming a part of this specification, in which—

Figure 1 shows the manner of applying my wallet to the body of the cotton-picker. Fig. 2 is a view of the wallet, exhibiting the peculiarities of the same.

Similar letters of reference indicate like parts in the two figures.

Those who are familiar with the present mode of picking cotton from the bolls are aware that in a very short time the fingers become soft and glazed, on account of the peculiar character of the cotton fiber, and that the fingers will slip in pulling the cotton from the bolls unless they are moistened, which is at present accomplished by putting their fingers in the mouth at every operation, the result of which is that the pickers soon become thirsty and require large quantities of water to quench their thirst, which is a loss of time, besides being injurious to the health.

Any improvement in the manner of picking cotton which will assist the picker and facilitate the operation is a great desideratum and amounts in the aggregate to a great saving in expense and time, and enables the planters to make more cotton, for it is a fact well known that they can plant and cultivate more cotton than they can pick with the same number of hands by the present slow method of gathering it.

My sack, which I denominate the "cotton-picker's wallet," has for its object the remedy of the defects of the present method of picking cotton with the hands, giving perfect freedom to the arms, so that both hands can be used, and furnishing the picker with a ready and convenient supply of water for the hands. The bag or wallet hangs in front of the picker,

like an apron, and is strapped around his waist by the straps B, and secured by a buckle or button. C C are the shoulder-straps for supporting the bag, for when filled it is quite heavy. The straps are crossed on the back, like a pair of suspenders, and buttoned in front to the edge of the fabric, as clearly shown by Fig. 2. The outside flap, A, is made quite large, so as to hang open, so that each hand can readily be placed in and taken out without using one to hold it open. In the bottom of this wallet are sewed two strips of wood, D D, and in the corners of the bag are sewed yokes E, so as to permit the strips to open quite wide for readily emptying the bag without removing it from the body. The two strips D D, when brought together and buttoned by a wood or metal button, a, with a long neck, prevent the cotton from falling out during the picking thereof.

G represents a pocket, of any oiled silk, rubber, or any water-proof material, which is sewed to the inside of the bag, as represented by the drawings, for holding a wet sponge. The outside portion of this pocket is perforated, so as to permit the water to the hands by a gentle pressure upon the bag. This pocket G is placed in a very convenient position, so that the hands can be moistened in the act of removing them from the bag, thus obviating the unpleasant and very inefficient practice of moistening the hands with the mouth.

These wallets are easily made and made very cheap, while their general form and arrangement of parts is gotten up with the special view to convenience to facilitate the work of the cotton-pickers.

I claim—

Applying a sponge or other equivalent device to a cotton-picker's wallet for the purpose of enabling the picker to readily moisten his fingers and thus facilitate his work, as herein described.

G. H. PEABODY.
